REVERSIBLE SETTING

Louis Shakter, Brooklyn, N. Y., assignor of fifty
percent to Frank Zoldo, New York, N. Y.

Application April 12, 1937, Serial No. 136,310

4 Claims. (Cl. 63—31)

The purpose of this invention is to provide improvements in reversible settings of the type used for brooches, clips, and the like, in which the setting is mounted between two pins, and means is provided for locking the setting with either side exposed.

The invention is a brooch, clip, or the like, having an opening therein, with a setting pivotally mounted in said opening, and adapted to be turned over to expose either side, in which the setting is provided with recesses in the opposite sides, into which a latch, positioned at one side of the opening, may snap to hold the setting with either side exposed.

Reversible settings have been provided for different types of jewelry and other articles, and some of these have been provided with spring pins for holding the setting in different positions, but it has been found advisable in jewelry, particularly of the type used for brooches and clips, to provide a positive lock in the form of a pin extending into an opening in the setting for positively holding the setting in either position; and it has also been found desirable to provide mounting means in the form of spring pins by which the setting may readily be removed, so that another setting may be used in its place.

The object of the invention is, therefore, to provide means for positively locking a setting in jewelry or the like, without means projecting from the setting, and, at the same time, by which the setting is positively held with either side exposed.

Another object is to provide a setting for jewelry or the like, in which the setting is interchangeable and, at the same time, reversible.

A further object is to provide means for holding a jewelry setting with either side exposed, in which the holding means comprises a pin slidably mounted on the piece of jewelry, and adapted to extend into openings in the opposite sides of the setting.

And a still further object is to provide a reversible setting for jewelry and the like having positive locking means, which is of a simple and economical construction.

With these ends in view the invention embodies an article of jewelry comprising a base and a setting, in which the setting is provided with oppositely positioned openings at right angles, with two of said openings adapted to receive pins forming bearings, and the other two of said openings adapted to receive a sliding latch positioned at one side of the base, and adapted to hold the setting with either face exposed.

Other features and advantages of the invention will appear from the following description taken in connection with the drawing, wherein:

Figure 1 is a view showing a front elevation of a brooch with a reversed setting. 5

Figure 2 shows a rear view of a brooch of an alternate design, in which the back is plain.

Figure 3 is a similar view showing another alternate design with parts omitted, and in which the setting is removable. 10

Figure 4 is a cross section on an enlarged scale, showing another alternate design, in which the setting is held by a spring pin.

Figure 5 is a view showing a clip with a reversible setting. 15

Figure 6 is a similar view showing a scarf pin with a reversible setting.

Figure 7 is also a similar view showing a ring with a reversible setting.

In the drawing the device is shown as it may be made, wherein numeral 1 indicates a base representing an article of jewelry and the like, numeral 2 a reversible setting, and numeral 3 a latch. 20

The base 1 may be in the form of a brooch, 25 as shown in Figures 1 and 2, in which the face may be covered with marcasite settings, or may be plain as shown, or may be of any type or design. This base may also be in the form of a clip as shown in Figure 5, or of a scarf pin or 30 ring, as shown in Figures 6 and 7, or may be shaped to form any other article as may be desired.

In the design shown the setting 2 is pivotally mounted by pins 4 and 5 extending into recesses 35 6 and 7 in the opposite sides, as shown in Figure 2, and with the setting mounted in this manner it will be noted that it may readily be turned over to expose either side, and one side may be plain or provided with marcasite settings, or 40 may have an initial as shown in Figure 5, or may be covered with an enamel of any color, or the sides may be formed in any manner.

It is preferred to hold the setting 2 by a simple slidably pin forming a latch 3, which is slidably 45 mounted in a bearing 7, and provided with a head 8 by which it may be moved outward or inward. The setting may also be provided with a lug 9 to limit the outward movement to prevent losing the latch. The end of the latch 50 member 3 extends into a recess 10 in the setting, as shown in Figure 2, and a similar recess 11 is provided in the opposite side, and it will be noted that with the latch 3 withdrawn the setting 2 may be turned over, and the latch may be in- 55

serted into the recess 11 to hold the setting with the opposite side exposed. The base 1 may also be provided with a pin 12 by which it may be held to a garment or the like.

5 It will be understood that this particular mounting involves the use of four recesses positioned at right angles in the sides of the setting with pins forming bearings extending into two oppositely positioned recesses, and with the other 10 two recesses provided to receive the end of a latch for locking the setting, and the type of bearings or latch may be changed as desired.

It will also be understood that the latch 3 may be formed as shown in Figure 3, in which it is indicated by the numeral 13, and in which it is mounted in a bearing 14 with a spring 15 around a pin 16 and engaging the end of the latch 13, and also the inner end of the bearing, thereby resiliently holding the latch outward, and the 20 latch is provided with a head 17 by which it may readily be withdrawn to release the setting.

In this design the latch extends into recesses 18 and 19, similar to the recesses 10 and 11, in the setting 20 in the base 21, and it will be noted 25 that this type of latch may be used with the bearings shown in Figure 2, or the bearings may also be formed with spring pins 22 and 23 resiliently held in bearings 24 and 25 by springs 26 and 27, and these pins are provided with heads 28 and 29 30 by which they may readily be drawn outward to release the setting 20, so that one setting may be removed and another inserted, providing a greater variety of changes.

The device shown in Figure 4 is merely an enlarged detail, showing a section through the brooch shown in Figures 1 and 2, with a spring latch of an alternate design for holding the setting, and showing in detail the relative positions of the recesses in the setting for receiving the 40 latch. In this design the base is indicated by the numeral 30, the setting by the numeral 31, and the latch by the numeral 32, and the latch is slidably held in a tubular bearing 33, and provided with a knob 34, and is resiliently held 45 by a spring 35. The inner end 36 of the latch extends into a recess 37 in the setting, and the opposite side of the setting is provided with another recess 38 also positioned to receive the end 36 of the latch with the position of the setting 50 reversed about the bearings formed by pins extending into the recesses 39 in the opposite sides of the setting. It will be noted that the recesses 37 and 38 are positioned above and below the center of the bearing formed at the point 39, 55 making it possible to hold the setting with the surfaces parallel with the base in either position.

The clip 40 shown in Figure 5 is provided with a setting 41 pivotally mounted on pins 42 and 43, and held with the setting in either position 60 by a latch 44 shown in dotted lines. The scarf pin 45 shown in Figure 6 is also similar, in that a setting 46 is pivotally mounted by pins 47 and 48 in the frame, and this is held in either position by a latch 49. The pin 50 may be attached to 65 the back of the frame 45 at any point or by any means. The ring 51 shown in Figure 7 is also similar in that a setting 52 is pivotally mounted on pins 53 and 54 with a latch 55 in a recess in the under-side of the ring extending into recesses 70 56 and 57 in the opposite sides of the setting.

It will be understood that other changes may

be made without departing from the spirit of the invention. One of which changes may be in the shape or design of the setting, as this may be of any other shape instead of round as shown, another may be in the use of the device in the setting of any other type, such as for a stone without a metal base or frame, and still another may be in the use of several settings in one article of jewelry, or in any combination of the settings with jewelry, as may be desired.

5 It will be understood that although the pins upon which the setting is mounted are shown vertically positioned, and the latch horizontally positioned these may be reversed, or the pins may be positioned at any angle, and the latch may also be positioned at any angle in relation to the pins, instead of the right angle as shown and described.

15 The construction will be readily understood from the foregoing description. In use the device may be provided as shown and described, and although it is preferable to use this mounting for brooches, clips and the like, it will be understood it may be used for jewelry of any type. The jewelry may also be provided with one 20 or any number of settings, and these may be marcasite on one side and plain on the other, or provided with initials, monograms, or any characters or designs and with the setting reversible 25 or interchangeable. A different color setting may be used to correspond with the color of a dress or garment, and with the setting mounted in this manner it has no objectionable pins or projections extending therefrom, as all of the movable parts are incorporated in the base or mounting.

30 Having thus fully described the invention, what I claim as new, and desire to secure by Letters Patent, is:

1. A reversible setting for jewelry and the like, 40 comprising a base having an opening therein, a setting pivotally mounted in said opening, and a latch slidably mounted on the under-side of the base and at one side of the opening, and adapted to extend into a recess in one side of the setting 45 with one face thereof exposed, and also into a recess in the opposite side of the setting with the position of the setting reversed; characterized in that the setting is formed with oppositely positioned recesses spaced at right angles, with two 50 of said recesses adapted to receive pins upon which the setting is rotatably mounted, and with the other two of said recesses adapted to receive the latch, with the setting turned in such a position that said recesses register with the latch.

55 2. A jewelry setting as described in claim 1, further characterized in that the latch comprises a pin slidably mounted in a bearing on the under-side thereof, and provided with means for limiting the movement thereof.

60 3. A jewelry setting as described in claim 1, further characterized in that the latch is resiliently held, with the end thereof extending into a recess in the setting.

65 4. A jewelry setting as described in claim 1, further characterized in that the setting is mounted by resiliently mounted pins adapted to be moved outward to remove and replace the setting.

LOUIS SHAKTER. 70
